UNITED STATES PATENT OFFICE.

MALCOLM COOPER, OF BALHAM, ENGLAND, ASSIGNOR TO THE H. T. C. ELECTRICAL CO. LIMITED, OF LONDON, ENGLAND, A BRITISH COMPANY.

HOLDER FOR THERMIONIC VALVES.

Application filed August 26, 1924. Serial No. 734,292.

To all whom it may concern:

Be it known that I, MALCOLM COOPER, a subject of the King of Great Britain and Ireland, and a resident of Balham, county of London, England, have invented a certain new and useful Improvement in Holders for Thermionic Valves, of which the following is a specification.

This invention relates to thermionic valves having caps with four or more pins or legs so arranged or positioned on the cap as to ensure that they can only be made to engage with their appropriate sockets or contacts in the holder.

The present invention provides a holder in which the minimum distance between the various contacts is that of the valve legs or prongs themselves and in which allowance is made for any irregularities in position of said valve legs and contact is made by means of L-shaped or U-shaped springs longitudinally aligned with and inwardly inclined towards the valve legs, the outer sides of which make longitudinal sliding contact with increasing pressure against the curved inner sides of the spring when the valve is put into position, the said springs being secured to a ring or other suitably shaped piece of good insulating material, adapted to be secured to any existing panel or board, or being bolted to the underface of a mould of insulating material adapted to be secured to a board of poor insulating material, so that in either case the said springs coincide with the positions of the valve legs when said valve is in position. By this means the valve holder has high insulation resistance, due to the wide spacing of the contact springs, and low self-capacity owing to the small amount of metal in the springs.

The invention is illustrated by the accompanying drawings, wherein:—

Figure 1 is a plan view of a holder for attachment to a panel.

Figure 2 is a sectional view thereof.

Figure 3 is a plan view of the template used when drilling the holes in the holder.

Figure 4 is a plan view of a holder for attachment to a board of poor insulating material.

Figure 5 is a sectional view thereof.

Figure 6 is a view of a modified form of device.

Like numerals of reference indicate corresponding parts in the several figures.

Referring to the drawings, the holder consists of a ring 1, or mould-shaped piece 1¹, of good insulating material of any suitable thickness, say $\frac{1}{4}$ inch, the internal diameter of the ring 1 or mold 1¹ being slightly greater than the space occupied by the valve legs.

L-shaped springs 2 are provided each with one arm extending outwards and holed for external connection and bolted or riveted to one face of the ring 1 or mould 1¹ aforesaid at suitable points to coincide with the positions of the valve legs, whilst the other arms of said springs project into and through the ring or from the mould towards the board and are curved or bent from the same centre as the valve legs in such manner that each spring will engage and make contact with one of the prongs or legs of the valve when the same is in position, external connection being made either from the bolts 3 holding said L-shaped springs 2, or from the arms by which the springs are fixed, the arms extending outwards and used as soldering tags, or, if necessary, both arrangements may be employed.

U-shaped springs 2¹ may be used with their inner arms curved or bent to ensure good contact with the valve legs and with the outer arms holed like those of the L-shaped springs 2 for use as externally connecting or soldering tags. The end parts of springs 2 and the middle parts of springs 2¹ have countersunk holes to receive countersunk headed bolts so that the insulating ring 1 can be easily fitted to the panel without recessing the latter to admit the bolt heads. The insulating ring 1 is also fitted with metal inserts or bushes 3¹ to accommodate the bolts, the outer ends of which inserts are also countersunk to suit the countersinking of the springs and bolt heads. In the mould 1¹ the bolts are fitted with flat sided nuts 4 or with cylindrical screwed collars of such thickness or depth as will slightly exceed the depth of the supporting and spacing rim or legs of the mould 1¹ and will take the strain therefrom when the mould is secured to a panel or board.

In practice, the fiber or other insulating

ring 1 or mould 1¹, as the case may be, is secured by two or more screws 4¹ to any existing panel or board 5, so that the springs 2¹ or 2 project downwards, as in Figures 1 and 5, and coincide with holes 6 drilled in the panel or board 5, Figure 2, or mould 1¹, Figure 5, for the reception of the valve legs, the diameter of said holes 6 being larger than is otherwise necessary to accommodate

10 any irregularity in the position of the valve legs as sometimes occurs, said holes 6, if desired, also being countersunk to accommodate the usual practice of soldering connections to the top of the valve legs.

15 The valve being inserted, the bottom of the valve cap 7 lies flush with the top of the panel 5, or the mould 1¹, as the case may be, and the pins or legs 8 project through it and make contact with their respective 20 springs 2 or 2¹, and in this manner is the valve firmly held in position.

When using the ring form of holder, there will also be furnished a template 9 provided with the holes whereby correct drilling position of the holes necessary for panel mounting can be obtained.

It is obvious that the maximum insulation is obtained owing to the fact that the minimum distance between two contacts is that 30 of the valve legs themselves. Further, it is also impossible to make contact between the wrong electrodes and damage the valves, owing to the fact that contact is not made until after right position has been determined by the standard arrangement of valve 35 legs or pins.

If desired, the bolts 3 may, as shown in Figure 6, be lengthened so as to extend through the panel 5 and be locked thereto 40 by nuts 10.

I claim:

1. A holder for thermionic valves with a plurality of pins or legs and suitable for fixing to a panel, comprising a ring of insulating material, contact springs each with one arm extending outwards, holed for external connection and secured to the said ring at a suitable interval from the adjacent springs so as to coincide with the positions

50 of the valve legs and holes in the panel, and with the other arm projecting into and through the ring and longitudinally aligned with and inwardly inclined towards the corresponding valve leg and curved from the same centre, a bolt through the outwardly 55 extending arm of each contact spring fitted with nuts, a metal insert to accommodate each bolt and screws for fixing the ring to the panel.

2. A holder for thermionic valves with a plurality of pins or legs and suitable for fixing to a panel, comprising a ring of insulating material, U-shaped contact springs each with one arm extended outside the ring and holed for external connection, with 60 the middle part secured to the ring at a suitable interval from the adjacent springs so as to coincide with the positions of the valve legs and holes in the panel, and with the inner arm projecting into and through the ring and longitudinally aligned with and inwardly inclined towards the corresponding valve leg and curved from the same centre, a countersunk headed bolt through the middle part of each contact 70 spring fitted with nuts, a metal insert with countersunk end to accommodate each bolt and screws for fixing the ring to the panel.

3. A holder for thermionic valves with a plurality of pins including in combination 80 with a panel board having pin receiving openings, a ring of insulating material having openings, a plurality of contact springs of angular formation and provided with openings for registering with the openings 85 in the insulating ring and an arm portion of said springs extending longitudinally with respect to the axis of the valve pins and inclined across the path of such pins, headed fastenings for passing through the 90 registering openings of the contact springs and the ring of insulating material, and other fastenings for connecting the ring of insulating material to the panel board.

In testimony whereof I have affixed my 95 signature hereto this 12th day of August 1924.

MALCOLM COOPER.
